NILS PETER ERIK ANDERSEN, OF ELM GROVE, WISCONSIN, AND MAURICE B. BRADLEY, OF CLEVELAND, OHIO, ASSIGNEES TO HARNISCHFEGER CORPORATION, OF MILWAUKEE, WISCONSIN, A CORPORATION OF WISCONSIN

GRAPPLE

Application filed September 10, 1931. Serial No. 562,008.

This invention relates to an improvement in grapples which, although especially designed and adapted for use in handling crated articles such as crated electrical mechanical refrigerators, is also designed for handling various other diverse types of articles.

Among the objects of the invention are to provide a novel type of grapple designed and adapted to securely and effectively grip and support the object being handled especially where the object is crated whereby to insure safe and expeditious transfer of the articles from one place to another. In carrying out this purpose of the invention the grapple is designed to straddle the articles and grip and hold the same from the outside as, for example, under external ledges or cleats of its crate or the like when the articles are crated.

Another object of the invention is to provide a grapple of this character which may be readily lined up with one or a plurality of articles to be handled and automatically brought into gripping engagement with the articles without the necessity of a ground crew, or of any operators in the region of the articles, the grapple being so constituted that by appropriately moving the same vertically and horizontally, automatic gripping engagement of the grapple with the articles is insured. In this connection, it is to be understood that the grapple is used in conjunction with an overhead crane and is so organized and constituted as to be controlled in its action by the operator of the crane.

A further object of the invention is to provide for the release of the articles when they are transferred to the point of deposit.

The invention also provides for the ready adaptation of the grapple to the handling of articles of different sizes. Furthermore, provision is made for effective gripping engagement of the grapple with the article notwithstanding the provision of interfitting structure on portions of the articles. For example, in handling crates the grapple is provided with a plurality of sets of grippers for each crate, the grippers being designed to engage beneath horizontal cleats on the crates. In some instances, vertical cleats or the like may interfere with the action of the grippers

but this does not impair substantial, secure and safe gripping engagement as the remaining sets of grippers have ample capacity to securely engage and grip the crate.

A further object of the present invention is to provide a grapple having these advantages and capacities and which is simple and durable in construction, reliable and safe in operation, easily controlled, comparatively inexpensive to manufacture and economical in respect of operating and maintenance costs.

In carrying out the present invention the grapple is utilized with the conventional or well known type of overhead crane. Such a crane has, as is well known, a motor driven bridge which moves along overhead tracks. The motion of the bridge may be considered longitudinal in that it travels back and forth along an aisle or area of the building. On the bridge a transversely movable truck is supported and rides back and forth on a track extending transversely on the bridge. Motor driven drums are provided on the truck and act to raise and lower ropes or cable arrangements. On the ropes or cables controlled by the drums the grapple embodying the present invention is mounted or suspended so that the grapple may be raised and lowered from the drums, moved transversely with the truck and moved longitudinally with the bridge. The grapple arrangement embodying the present invention consists generally of a pair of parallel side frame members which may be interconnected for transverse adjustment relative to each other and which are supported by pulleys from the cables. The side frame members carry transversely aligned and vertically depending grapple arms, and grapple arms of one side frame member may be longer than the grapple arms of the other side frame members. Each grapple arm is provided with a spring projected gripping or grapping element or finger.

With such an arrangement the grapple may be readily aligned with the crates or other articles to be handled by so moving the crane as to bring the lower ends of the longer arms of the grapple into engagement

with the upper portions of the crates. When properly positioned in this manner the grapple is lowered by the crane until the spring projected grappling fingers or elements of the arms snap into gripping engagement with the horizontal cleats or other similar structure provided around the upper end portions of the crates. The crane may be then used to elevate the grapple and the crates engaged therewith to transport the crates to a place of deposit. The crane is then operated to lower the grapple and its crates and deposit the crates in the selected place. The operator of the crane then sets into motion a releasing mechanism which functions to withdraw the gripping fingers or elements from beneath the ledges and this, of course, against the action of their biasing springs. Prior to this releasing action the grapple has been lowered sufficiently to disengage the gripping fingers from the ledge. With the gripping fingers retracted the crane may be utilized to raise the grapple clear of the crates and leave them at the point to which they have been placed.

The side frame members being interconnected for transverse adjustment provide for the adaptation of the grapple to various sizes of crates.

Other objects and advantages reside in certain novel features of the construction, arrangement and combination of parts which will be hereinafter more fully described and particularly pointed out in the appended claims, reference being had to the accompanying drawings forming a part of this specification and in which:

Figure 1 is a view in side elevation showing a grapple embodying the present invention;

Figure 2 is a view in transverse vertical section taken in the plane of line 2—2 of Figure 1 with parts shown in elevation for the sake of simplicity in elevation;

Figure 3 is a view in longitudinal vertical section taken on line 3—3 of Figure 2;

Figure 4 is a fragmentary sectional view of one of the grapple arms, illustrating its gripping element in released position; and

Figure 5 is a fragmentary view partly in plan and partly in horizontal section showing one manner of adjustably interconnecting the side frame members.

Referring to the drawings, it will be seen that the grapple embodying the present invention comprises a pair of side frame members designated at 1 and 2 and which may be constituted of channel irons. The side frame members are interconnected with each other so as to constitute a frame for the grapple and preferably this interconnection is of such character as to provide for transverse adjustment of the frame members relative to each other. One mode of effecting such an ad-

justable interconnection is shown for the sake of illustration in the drawings and consists in the provision of two pairs of slidably interconnected transverse frame members, the members of each pair being designated at 3 and 4, the member 3 of each pair being rigidly secured at one end to the side frame member 1 and terminating at its other end in spaced relation to the side frame member 2, whereas the other transverse frame member 4 is rigidly secured at one end to the side frame member 2 and terminates at its other end in spaced relation to the side frame member 1. The transverse frame members 3 and 4 of each pair are interconnected for relative sliding movement by box-like guides 5, there being two guides 5 for each pair of frame members 3 and 4. Each of the guides 5 is secured to and carried by a vertical hanger plate 6 which is interposed between the members of each pair of transverse frame members and which is in turn suspended by yokes 7 from pulleys 8. Pulleys 8 are hung in the bight portions of a cable arrangement C which depends from drum and guide pulleys of the truck of an overhead traveling crane designated diagrammatically at T and which has a motor driven drum D controlling the paying out and hauling in of the cables and thereby effecting raising and lowering of the grapple.

Depending from the side frame members 1 and 2 are a plurality of vertically disposed grapple arms designated at 12 and 13, respectively. The upper ends of the grapple arms 12 and 13 are securely fastened to their side frame members 1 and 2, respectively, and the grapple arms 12 are transversely aligned with the grapple arms 13. The grapple arms 12 and 13 are of similar construction and differ only in that the grapple arms 13 are longer than or project downwardly beyond the grapple arms 12. Each of the grapple arms 12 and 13 has a built up lower end of tapered formation as indicated at 14 and above its lower end is of channel form. Within the channel portion of each grapple arm, a gripping finger or gripping element designated at 15 is provided and has a bearing 16 pivotally supported as by means of a pin 17 on the flanges of its arm. A spring 18 is associated with each gripping element to bias the same to projected position. Below its bearing portion 16 each gripping element is provided with a projection or tail-piece 19. The gripping elements of the arms 12 and 13 are transversely aligned as illustrated in the drawings.

In order to provide for the retraction of the gripping elements 15, that is, for the movement of these elements, to what may be termed their released or releasing position, a releasing strip 20 is slidably fitted in the channel portion of each grapple arm and is constrained to vertical sliding movement by a guide plate 21 extending between and se-

cured to these flanges and having guiding engagement with the strip 20 slideable therewith. Normally, the lower end of each strip 20 occupies the position shown in Figure 2, in which position the spring 18 is effective to project the gripping finger since the tail-piece 19 may swing up against the body portion of the grappling arms. If, however, the strips 20 are depressed or moved downwardly their lower ends coact with the projections 19 of the gripping fingers to swing the projections and the gripping fingers in a clock-wise direction as viewed in Figure 4 whereby to retract the gripping fingers, that is, to move them to released position.

Suitable means may be provided for actuating the releasing strips and in the present instance means is proposed which acts to simultaneously depress or elevate the releasing strip.

In the construction shown for the sake of illustration the upper end of each releasing strip 20 is provided with a pin 22 which is secured to, extends transversely of and projects laterally beyond its strip. The pins 22 are operatively fitted and inclined camming slots 23 provided in vertical flanges of longitudinally shiftable angular bars 24. The angle bars 24 have their horizontal flanges constrained to sliding movement over the upper surfaces of the transverse frame members 3 and 4 by means of guide clips 24' shown in Figure 2. For the purpose of shifting the bars 24 back and forth and thereby cause the slots 23 to coact with the pins 22 to raise and lower the releasing strips 20, racks 25 are secured to portions of the angle bars 24 and mesh with elongated pinions 26 fixed at the outer end of a jack shaft 27 supported for rotation in suitable bearing brackets 28 and driven from an electric motor 29 by suitable reduction gearing such as a worm and worm wheel 30.

The support for the motor 29, for the brackets 28 and the housing for the worm gearing 30 is provided by longitudinal channels 50 which are arranged in spaced parallel relation and are secured to and extend between the hanger plates 6; preferably the channels 50 are welded to the hanger plates 6 at their ends. Extending transversely of these channels 50 and secured thereto are transverse supporting webs 51 and 52 on which the motor 29 and housing for the worm gear 30 are suitably secured.

Ordinarily the transverse adjustment of the frame members 1 and 2 after having been set is not disturbed for a considerable time, for the reason that usually the grapple handles quite a number of crates or the like of the same size. However, when a different size crate or other article is to be handled an appropriate transverse adjustment is effected. Suitable means is provided for effecting this

transverse adjustment and in the present embodiment of the invention this means is shown for the sake of illustration as consisting of a longitudinal extending shaft 31 supported for rotation in the plates 6. On the opposite sides of each plate 6 oppositely disposed crank arms 32 and 32' are pinned or otherwise suitably secured and are connected by links 33 and 34 to the transverse members 4 and 3, respectively, one end of each link being pivotally connected to a crank arm and the other end of each link being suitably connected to its transverse frame member. Any suitable means may be provided for rotating the shaft 30. For the sake of simplicity in illustration, this means is shown as consisting of a hand wheel 40 fixed to a transverse shaft 41 having driving connection with the shaft 30 through worm gearing 42. Obviously, the shaft 41 may be motor driven if desired.

It will be understood from a comparison of Figures 1 and 2 that the grapple lends itself to a four-point suspension from the overhead crane. As illustrated in Figure 1, the wire W leads from the motor 29 to the crane so that the control of the motor may be exercised in a well known manner by the operator of the crane.

The worm gearing 42 is contained in a suitable housing 43 which is secured to and depends from transverse channels 44 appropriately secured, as, for example, welded to the supporting channels 50.

It will be understood that when the frame members 1 and 2 are shifted or adjusted transversely that the bearing provided for the shaft 41 and the bearing brackets 28 provided for the shaft 27 slide freely axially or longitudinally of their shafts. The specific means disclosed for imparting the actuating force to the releasing strips and the actuating force to the shaft 30 is selected merely for the sake of illustration and it is to be understood that in this and in other respects various changes in the size, form and arrangement of the parts may be made without departing from the spirit of the invention or the scope of the subjoined claims.

However, the means for actuating the strips 20 and the shaft 30 preferably include or have associated therewith some means for automatically holding the shaft and the strips in adjusted position. For example, in the construction illustrated, the worm gearing is self-locking and holds the parts in any adjustment. As illustrated in Figure 2, the transverse frame members 3 and 4 are slotted to enable these frame members to move relative to the shaft 30 when the side frame members 1 and 2 are adjusted relative to each other.

While one purpose of the transverse adjustment is to adapt the grapple for use with crates or articles of different sizes it is obvious that the movement of the grapple arms

toward and away from each other, especially where this movement is motorized, will be advantageous for other purposes. For example, where the grapple is engageable with a row of crates or articles which are somewhat out of line a movement of this character enhances the capacity of the grapple to cope with the somewhat staggered arrangement of the crates or articles.

10 The invention claimed is:

1. A grapple of the character described comprising a frame having spaced side members, a plurality of grapple arms carried by and depending from said side members, each of said grapple arms having an inwardly and upwardly directed gripping element, said arms being adapted to straddle the article to be handled and to position the gripping elements for engagement beneath the ledge-like structure on the outside of the article, means for yieldably biasing the gripping elements to gripping position and a common release for said gripping elements.

2. A grapple adapted to be suspended from the cables of an overhead crane and comprising hanger plates having pulleys suspended from said cables, a frame having side frame members and slidably interfitted transverse frame members, means coacting with the hanger plates and with said transverse frame members for supporting the frame from the cable arrangement, means for transversely adjusting said transverse frame members and securing the same in any transverse adjustment, and grappling means carried by the side frame members and adapted to straddle the articles to be handled and to have gripping engagement therewith from the outside.

3. A grapple of the character described comprising a frame having side frame members, a plurality of grapple arms depending from each side frame member and adapted to straddle the articles to be handled, said grapple arm having gripping elements adapted to grip the articles to be handled from the outside, the grapple arms depending from one side member of the frame being longer than the grapple arms depending from the other side member and being cooperable with the articles to be handled to facilitate alignment of the grapple therewith.

4. A grapple of the character described comprising a frame having side frame members, transverse frame members connected to each side frame member, means interconnecting the transverse frame members with relative sliding movement, a motor driven shaft carried by said means, cranks carried by said shaft, links actuated by said cranks and connected by said side member, and grappling means carried by said side frame members and adapted to straddle the articles to be handled and to have gripping engagement therewith from the outside.

5. A grapple of the character described

comprising a plurality of grapple arms, means supporting said grapple arms to straddle the articles to be handled, a pivoted gripping finger mounted on each of said grapple arms, a spring for urging said gripping finger to gripping position, and means for swinging the gripping finger to released position.

6. A grapple of the character described comprising a plurality of grapple arms carried by said frame and depending therefrom, means supporting said grapple arms to straddle the articles to be handled, a pivoted gripping finger mounted on each of said grapple arms, a spring for urging said gripping finger to gripping position, a slidably release strip mounted on each grapple arm and cooperable with the gripping finger thereof to swing the gripping finger to released position when slid in one direction, and means for sliding the releasing strips.

7. A grapple of the character described comprising a plurality of grapple arms carried by said frame and depending therefrom, means supporting said grapple arms to straddle the articles to be handled, a pivoted gripping finger mounted on each of said grapple arms, a spring for urging said gripping finger to gripping position, a slidably release strip mounted on each grapple arm and cooperable with the gripping finger thereof to swing the gripping finger to released position when slid in one direction, means for sliding the releasing strips consisting of a pair of shiftable bars, a camming pin and slot connection between each of said strips and one of said bars, and means for shifting said bars.

8. A grapple of the character described including spaced grapple arms having inwardly and upwardly directed gripping elements, and means for shifting said elements from a gripping to a released position, one of said grapple arms being longer than the other to facilitate engagement of the grapple with the article to be handled.

9. A grapple adapted to be suspended from the cables of an overhead crane and comprising hanger plates having pulleys suspended from said cables, a frame having side frame members and slidably interfitted transverse frame members, box-like guides carried by said hangers and through which said transverse frame members slide, means for transversely adjusting said transverse frame members and grappling means carried by said side frame members and adapted to straddle the article to be handled and to have gripping engagement therewith from the outside.

In witness whereof, we hereto affix our signatures.

NILS PETER ERIK ANDERSEN.
MAURICE B. BRADLEY.
